DESIGN FOR A REFRIGERATED DISPLAY AND STORAGE CABINET

Arthur Schupp, New York, N. Y.

Application December 9, 1944, Serial No. 116,811

Term of patent 14 years

(Cl. D80—11)

To all whom it may concern:

Be it known that I, Arthur Schupp, a citizen of the United States of America, residing at New York city, in the county and State of New York, have invented a new, original, and ornamental Design for a Refrigerated Display and Storage Cabinet, of which the following is a specification, reference being had to the accompanying drawing, forming part thereof.

Fig. 1 is a front perspective view of a refrigerated display and storage cabinet showing my new design;

Fig. 2 is a rear perspective view; and
Fig. 3 is an end elevational view thereof.

I claim:

The ornamental design for a refrigerated display and storage cabinet, substantially as shown.

ARTHUR SCHUPP.
